PHILIP H. DOWLING, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL TRANSLATING APPARATUS

Application filed December 12, 1930. Serial No. 501,799.

My invention relates to electrical translating apparatus, and particularly to apparatus involving relays of the amplifying transformer type.

- 5 The output winding of a relay of this type ordinarily has comparatively low impedance, so that when two or more such relays are connected in multiple across a load, the output winding of a relay which is deenergized 55
 10 may form a path of comparatively low impedance for the output winding of an energized relay, thereby diverting from the load a considerable proportion of the output of the energized relay.
 15 One feature of my invention is the provision, in relays of this character, of means for causing the output winding to have a relatively high impedance when the relay is deenergized, and a relatively low impedance
 20 when the relay is energized, thereby preventing a deenergized relay from shunting any considerable part of the output of an energized relay from the load.

I will describe one form of apparatus embodying my invention, and will then point out the novel features thereof in claims.

In the accompanying drawings, Fig. 1 is a diagrammatic view showing one form of apparatus embodying my invention. Fig. 2 is 30 a view showing the structure of each of the relays D of Fig. 1.

Similar reference characters refer to similar parts in each of the views.

Referring first to Fig. 1, the reference characters D¹ and D² designate relays of the amplifying transformer type, each of which comprises an output winding 9 and a control winding 8. The two output windings 9 are connected in multiple across a load 11 11 which, as here shown, is a railway track circuit. Relay D¹ comprises a primary winding 4 connected with a source of alternating current G¹, the frequency of which may, for example, be 100 cycles per second. The control winding 8 is at times connected with a source of direct current F¹ through a front contact 10 of a relay E¹, and the parts are so arranged that when contact 10 is open, relay D¹ delivers no current to the load, whereas, 50 when contact 10 is closed, relay D¹ delivers

100 cycle current to the load. The parts associated with relay E² are similar to those associated with relay E¹, except that the source of current G² is of a different frequency, such for example as, 150 cycles per second. It follows that when contact 10 of relay E² is open, relay D² will deliver no current to the load, but that when relay E² is energized, relay D² will deliver 150 cycle current to the load.

Assuming now that relay D² is energized and relay D¹ is deenergized, it will be apparent that unless the impedance of winding 9 of relay D¹ is high, this winding will shunt from the load a considerable part of the current delivered by relay D². A similar condition would exist when relay D¹ is energized and relay D² deenergized. In accordance with my present invention, I provide means for increasing the impedance of each 70 output winding 9 at all times except when the associated control winding 8 is energized.

Referring now to Fig. 2, each relay D comprises three magnetizable cores A, B and C. Cores A and C each have three legs 1, 2 and 3, whereas, core B has only two legs 12 and 13. The primary winding 4 encloses leg 3 of core A and leg 13 of core B, whereas, the output winding 9 encloses leg 12 of core B and leg 3 of core C. The control winding 8 is placed 75 on the middle leg 2 of core A. An auxiliary winding 5 is placed on the middle leg 2 of core C, and means are provided for supplying this winding with current when and only when the control winding 8 is energized. As 80 here shown, winding 5 is connected with a winding 6 on core B through a rectifier R, so that the flux which links windings 4 and 9 creates current in winding 6 and this current produces direct current in winding 5.

When contact 10 of relay E is open, so that the control winding 8 is deenergized, the core A has very high permeability so that it then constitutes a magnetic shunt of low reluctance around leg 13 of core B. The result is that practically all of the flux due to the current in primary winding 4 will flow through core A instead of through core B because of the relatively much higher reluctance of core B due to the windings thereon. In other words, 90 100

substantially none of the flux from winding 4 will flow through windings 6 and 9. It follows that the output winding 9 is deenergized, and that the same thing is true of the auxiliary winding 5. The permeability of core C is then high, with the result that the impedance of the output winding 9 is high. When contact 10 is closed, however, so that winding 8 is energized, the permeability of core A is decreased, with the result that the flux due to current in winding 4 is forced to flow through core B. This flux creates alternating current in the winding 9, and also in the winding 6 with the result that direct current is supplied to the auxiliary winding 5. This current in winding 5 decreases the permeability of core C thereby decreasing the impedance of the output winding 9.

The middle leg of each core A and C is provided with a copper sleeve 7 to prevent the flow of alternating current through these legs.

When an auxiliary load, such as a lamp, is to be supplied with current from each relay 25 when and only when the relay is energized, it is obvious that this load may be connected with winding 6. It is also obvious that winding 5 may be energized by means other than winding 6 such, for example, as by part 30 of the current supplied to the control winding 8 or by part of the current furnished by the output winding 9.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a transformer having a primary winding connected with a source of alternating current, an output winding inductively coupled with said primary winding and normally having high impedance, means for normally shunting flux due to current in said primary winding away from said output winding, a control winding effective when energized to force flux due to current in said primary winding through said output winding, and means for reducing the impedance of said output winding when said control winding is energized.
2. In combination, a transformer having a primary winding connected with a source of alternating current, an output winding inductively coupled with said primary winding and normally having high impedance, means for normally shunting flux due to current in said primary winding away from said output winding, a control winding effective when energized to force flux due to current in said primary winding through said output winding, and means responsive to flux

linking said primary and output windings for reducing the impedance of said output winding.

3. In combination, a transformer having a primary winding connected with a source of alternating current, an output winding inductively coupled with said primary winding, means for normally causing said output winding to have high impedance, means for normally shunting the greater part of the flux due to current in said primary winding away from said output winding, and means including a control winding for forcing flux due to current in said primary winding through said output winding and reducing the impedance of said output winding when the control winding is energized.

4. In combination, three magnetizable cores A, B and C, a primary winding enclosing portions of cores A and B and connected with a source of alternating current, an output winding enclosing portions of cores B and C, a control winding on core A, a fourth winding on core C, and a fifth winding on core B connected with said fourth winding through a rectifier.

5. In combination, three magnetizable cores A, B and C, a primary winding enclosing portions of cores A and B and connected with a source of alternating current, an output winding enclosing portions of cores B and C, a control winding on core A, a fourth winding on core C, and means for supplying said fourth winding with current due to the flux flowing in core B.

6. In combination, three magnetizable cores A, B and C, a primary winding enclosing portions of cores A and B and connected with a source of alternating current, an output winding enclosing portions of cores B and C, a control winding on core A, a fourth winding on core C, and means for energizing said fourth winding when and only when said control winding is energized.

7. In combination, two transformers each having a primary winding connected with a source of alternating current, an output winding on each transformer inductively coupled with the primary winding on the same transformer and normally having high impedance, said output windings being connected in parallel, a control winding on each transformer arranged to be supplied at times with direct current, means for shunting flux due to current in each primary winding away from the associated output winding except when the associated control winding is energized, and means for reducing the impedance of each output winding when and only when the associated control winding is energized.

8. In combination, a primary winding connected with a source of alternating current, an output winding, a magnetizable core passing through said two windings, a second core

- passing through said primary winding and normally shunting most of the flux due to current in the primary winding away from said output winding, a control winding on
5 said second core which when energized reduces the permeability of such core and so forces most of the flux due to current in said primary winding through said output winding, a third core passing through said output
10 winding to normally increase the impedance thereof, an auxiliary winding on said third core arranged when energized to reduce the permeability of the third core and so reduce the impedance of said output winding, and
15 means for energizing said auxiliary winding when said control winding is energized.

In testimony whereof I affix my signature.
PHILIP H. DOWLING.
